UNITED STATES PATENT OFFICE.

ROBERT MURPHY, OF CANISTEO, NEW YORK.

ROTARY CHURN.

SPECIFICATION forming part of Letters Patent No. 238,519, dated March 8, 1881.

Application filed September 9, 1880. (Model.)

To all whom it may concern:

Be it known that I, ROBERT MURPHY, of Canisteo, in the county of Steuben and State of New York, have invented a certain new and useful Improvement in Securing the Covers to Rotary Churns and other Vessels; and I do hereby declare that the following is a full, clear, and exact description of the same, reference being had to the accompanying drawings, in which—

Figure 1 is a central vertical section of the upper part of the churn, cutting through the middle of the cover-fastening device; Fig. 2, a side view of the upper part of the churn, showing a front view of the cover-fastening device; Figs. 3, 4, and 5, views of the parts composing the cover-fastening device in detail.

Like letters designate corresponding parts in all of the figures.

A is a cover of my rotary churn, and is composed of the two parts A' and B. The part A' is preferably made of wood, and is so arranged as to snugly fit within the rim B of the cover, which fits over the head of the churn and rests upon an elastic cushion placed in the top of the staves, thereby keeping the cask in an air and water tight condition.

Firmly secured to each side of the cask is a plate, C, having upon its upper end a projection, H, to which is pivoted the bifurcated end of a lever, E. This lever also has formed near its upper end two projecting arms, arranged at right angles to the long arm of the lever, and so arranged that their outer ends bear against the connecting-bar G of the triangle D, and by this means always keep the lever in the center of the plate C. This lever is also so constructed that, in case of any irregularity in the metal rim B, the center at a bears

firmly against the connecting-bar G, so that when power is applied to lever E the bar G will give sufficiently to allow the said lever to pass beyond the dead-point, thereby locking all the parts firmly together. The triangle 45 D has formed upon its upper end a hook, g, for the purpose of keeping the cover always in position.

F is the strip of elastic material set into the top of the staves of the cask, and upon which 50 the cover rests.

It is evident that when not in use the lever and triangle rest against the side of the cask.

When the cask is ready for use the triangle is raised until the hooked end engages the 55 rim of the cover. The lever also is raised, and when the power is applied to the lever it is forced into the position shown in the drawings, thereby locking all the parts firmly together.

Having thus described my invention, what I claim as new, and desire to secure by Letters Patent, is—

1. In a rotary churn or other vessel, a cover-fastening device composed of a lever, E, 65 hinged to a bearing-plate, C, and provided with lateral arms, a hook, D g, having separated hinge-bearings, as described, and a slight elastic connecting-bar, G, all arranged and operating substantially as and for the purpose 70 herein specified.

2. In combination with the hooks D g D g and their tightening-levers E E and G G, the concave flanged metallic rim B surrounding the cover, substantially as and for the purpose 75 herein specified.

ROBERT MURPHY.

Attest:

T. WALTER FOWLER,
W. F. MORSELL.
